Philip K. Campbell, Jr.

UNITED STATES PATENT OFFICE.

CHARLES H. PHILLIPS, OF MALDEN, MASSACHUSETTS, ASSIGNOR TO PHILLIPS FLUSHING TANK COMPANY, OF PORTLAND, MAINE, A CORPORATION OF MAINE.

FLUSHING-VALVE.

1,209,753.

Specification of Letters Patent. Patented Dec. 26, 1916.

Application filed February 14, 1916. Serial No. 78,186.

To all whom it may concern:

Be it known that I, CHARLES H. PHILLIPS, a citizen of the United States, residing at Maplewood, Malden, in the county of Middlesex and State of Massachusetts, have invented certain new and useful Improvements in Flushing-Valves; and I do hereby declare the following to be a full, clear, and exact description of the invention, such as will enable others skilled in the art to which it appertains to make and use the same.

This invention relates to flushing-valves, such as are used in connection with water-closets, of the type in which a valve-member is opened as the result of a manual operation, and is then held open automatically, for a predetermined time, by means of a dashpot.

In devices of the kind in question it has been previously proposed to control the flushing valve by a dashpot inclosed within the valve-casing and filled with water. This arrangement has proved unreliable, by reason of the fact that the small escape-opening of the dashpot is liable to be choked by particles of solid matter suspended in the water, so that the action of the valve is rendered irregular and uncertain. For the foregoing reason, the most successful flushing-valves have been those in which the action is controlled by an air-check located outside of the valve-casing.

The use of an air-check as the sole means for controlling the valve is unsatisfactory, for the reason that the elasticity of the air permits a chattering action of the flushing-valve in the act of closing. Accordingly, it has been found desirable to use a water-filled dashpot in addition to the air-check, thus producing a comparatively complicated construction in which the uncertainties of operation, due to the dashpot, are more or less eliminated.

One object of the present invention is to improve the water-filled dashpot as to render its operation regular and certain, and thus avoid the necessity of using an air-check. To this end the dashpot of the present invention is provided with simple and effective means whereby choking of the restricted water-outlet is avoided, this improvement comprising, particularly, the use of a movable valve-member of spherical form for restricting the outlet, this member being located normally in an elongated pas-

sage and so arranged as to be always lifted from the passage at each operation of the flushing-valve, so that any particles of solid matter which have previously lodged in the restricted outlet may be surely dislodged and carried away by the flow of water.

Another feature of construction by which certainty and regularity of operation are insured resides in the means for returning the flushing-valve proper to its seat. In accordance with the present invention the main valve is subjected to a constant and predetermined force tending to close it, this force being uniform throughout the range of movement of the valve. This is accomplished by using a relief-valve in connection with the main valve and with a dashpot, a spring being interposed, which tends to produce a relative movement of the valve-members by which the relief-valve is closed. The effect of this arrangement, as will be explained hereinafter, is to cause the main valve to be subjected to a closing force which is automatically rendered substantially equivalent to that of the spring in question, although it is produced not by the spring, but by the weight of the valve supplemented by water-pressure against the top of the valve.

Other objects of the invention, and the features of construction by which they are accomplished, will be pointed out hereinafter, in connection with the description of the illustrated embodiment of the invention.

The accompanying drawing is a vertical sectional view of a flushing-valve embodying the present invention.

The invention is illustrated as embodied in a flushing-valve having a casing 5 of which the upper part 6 forms an inlet-chamber. This inlet-chamber may be connected with a source of water-supply by means of a screw-threaded branch 7. Below the inlet-chamber is an outlet-chamber 8, which communicates, through a passage 9 at the left-hand side of the casing, with an outlet-nipple 10.

Between the inlet-chamber and the outlet-chamber the annular seat 11 of the main valve is located, and the main valve has the form of a disk 12 provided, on its lower surface, with the usual gasket to engage the seat. The main valve is integral with a cylindrical upward extension 13, which slides within a tubular guide 14. This guide

and the valve-seat 11 are formed integral for convenience of construction, and a beveled ground surface at the lower end of the guide 14 fits against a corresponding surface 15 in a diaphragm which separates the inlet-chamber and the outlet-chamber. The guide is held in place by means of a screw-cap 16, which is sealed against the valve-casing and the guide by a gasket 17, so that 5 the cap and the upper part of the guide 10 form a closed chamber 40, which communicates with the inlet-chamber of the valve-casing only in so far as the rather loose fit between the parts 13 and 14 permits leakage 15 of water.

The dashpot, by which the operation of the flushing-valve is controlled, comprises a cylinder 19 formed integral with the casing 5, in which a piston 20 moves, this piston 20 being packed with the usual cup-leather so that its downward movement is resisted by the pressure of the contents of the cylinder. This dashpot constitutes, also, a hydraulic motor for opening the valve. The 25 piston of the motor is of less diameter than the seat 15 against which the guide 14 rests. Accordingly, upon removing the cap 16 the entire assemblage of guide, main valve, relief-valve and piston may be removed from 30 the casing 5, for the purpose of inspection or repair, and by the same operation access is afforded to the check-valve 30 and the stem 31. This construction simplifies equally the 35 assembling of the parts in manufacture or after they have been separated for the purpose aforesaid, the only packed joint which must be made being that afforded by the gasket 17 in the cap. The operation of the motor is controlled manually. For this purpose 40 a valve 21 is arranged to control an opening 22 leading from the inlet chamber 6 to a passage 23, through which water under pressure may flow, when the valve 21 is open, into the cylinder 19. The valve 21 45 is normally held closed by the water-pressure and by a spring 24. The valve 21 is opened by means of a hand-lever 28 connected to the outer end of a rock-shaft 27 which is journaled in the wall of the casing 5. Within the passage 23 an arm 25 is fixed 50 to the rock-shaft, and this arm engages a stem 26 projecting inwardly from the valve 21, so that by swinging the hand-lever upwardly the valve may be raised from its seat. 55 Since the hydraulic motor must act also as a dashpot to check the downward movement of the main valve 12, it is necessary that the water in the cylinder 19 be allowed to escape slowly through a small, and preferably 60 adjustable, opening. On the other hand, the opening through which water is introduced to the cylinder, when the motor acts as such to raise the main valve, should be large enough to permit a rapid action of the motor, so 65 that the piston will fully open the main valve

quickly and without the necessity of retention of the hand-lever 28 for any substantial length of time in its raised position. To provide suitable openings as just described, and to carry out that feature of the invention 70 which resides in provision against clogging of the outlet-passage from the cylinder, a valve-member 30 in the form of a ball is employed. This member cooperates with a slightly tapering passage 29 in a downward 75 extension from the bottom of the cylinder 19. The ball is supported normally upon the upper end of a stem 31, and its position and its diameter, with relation to the passage 29, is such that the ball nearly, but not quite, closes 80 the passage. Accordingly, a very narrow space is afforded, between the ball and the walls of the passage, for the escape of water when the piston 20 descends. On the other hand, when the valve 21 is open and the water 85 flows from the passage into the cylinder, the ball 30 is raised from its seat on the stem 31 and into the body of the cylinder, whereby the full area of the passage 29 becomes effective for the admission of water to the cylinder. 90

It will be apparent that if any particle of solid matter becomes lodged in the narrow space between the ball and the walls of the passage during the dashpot action of the 95 motor, this particle will be dislodged upon the next motor-action, owing to the movement of the ball from its seat, and thus permanent choking of the outlet passage is prevented. 100

Since it is necessary to provide an outlet from the passage 23 for the escape of the water discharged through the passage 29, the stem 31 is arranged to pass loosely through a nipple 32 projecting downwardly 105 from the passage. The space between the stem and the nipple is ample to permit the escape of the water during the dashpot action of the motor, while at the same time it is not large enough to prevent the piston 110 from being raised by the rapid inflow of water when the valve 21 is opened.

In order that the rate of movement of the piston 20, when performing its dashpot action, may be adjusted, the stem 31 is supported, at its lower end, within a sleeve 33 integral with the outlet-nipple 10, and an adjusting-screw 34, with a conical inner end, is arranged to engage and support the lower 115 end of the stem. By turning this screw inwardly the ball 30 may be raised so as to increase the outlet-opening, or the opening may be diminished, and the time of action of the dashpot increased, by turning the screw outwardly. 120

Under certain conditions of operation air may become trapped within the cylinder 19. It is undesirable to retain any substantial amount of air in the cylinder, as this will provide an elastic cushion which tends to 125

permit vibratory or chattering action of the parts during the closing movement of the main valve. In order to permit the ready escape of air from the cylinder, the cylinder 5 is provided with an opening 42 so located as to be uncovered by the piston at the upper end of its rising movement. The air, and more or less water, escapes through this opening, and it has the further advantageous result that it permits the escape of a current of water by which particles of solid matter, which might otherwise become trapped and collected within the cylinder, may be carried away at each operation of the mechanism. 10

15 The piston 20 is connected with the main valve 12 through a stem 35, which projects upwardly through the relief-opening in the main valve and which has a certain degree of vertical movement relatively to the valve. 20 This stem carries, at its upper end, a relief-valve 37 which cooperates with a seat 38 surrounding the relief-opening. The stem 35 is provided with guide-flanges fitting freely within the opening, and the stem, therefore, 25 does not prevent the flow of water through the opening.

Below the main valve the stem is provided with lugs 39 which engage the main valve and raise it from its seat, after the short amount of relative movement by which the relief-valve is first raised from its seat, during the rising movement of the piston. A spring 41, interposed between the main valve and the lugs 39, tends to produce a relative movement of the main valve and the relief-valve, by which the latter is closed. 30

40 The main valve-member 12, together with the cylindrical extension 13 and the cylindrical guide 14, constitutes a single-seated balanced valve of a well-known type, the construction being such that so long as the relief-valve is open, thus equalizing the pressure between the chamber 40 and the outlet-chamber 8, the pressure of the water in the inlet-chamber 6 has no tendency to prevent an opening movement of the main valve. Whenever the relief-valve is closed, however, water under pressure, which leaks in between the extension 13 and the guide 14, 45 will fill the balance-chamber 40 and assume the same pressure as the water in the chamber 6, thus holding the main valve firmly against its seat.

50 When the main valve is in raised or open position water flows from the inlet-chamber through four circular openings 18 in the guide 14, and thence through the opening controlled by the main valve and into the outlet-chamber 8. As the main valve falls, in its closing movement, the main flow of the water is first diminished and then cut off by cooperation of the lower edge of the main valve with the lower curved edges of the openings 18, so that a uniform downward movement of the main valve gives a

diminishing flow of water. In this manner provision is made for a heavy flow which will have a flushing action, followed by a diminished flow for the purpose of supplying water to provide a seal in the trap of 70 the water-closet.

75 The spring 41 has an important function in connection with the closing movement of the main valve. When the valve is in its normal position as illustrated, and the controlling-valve 21 is open, the rising movement of the piston 20 first produces an opening movement of the relief-valve, while the main valve remains closed. This is due to the fact that at this time the balance-chamber 80 40 is full of water under pressure, so that the main valve is held firmly to its seat. As soon as an escape for this water has been afforded by the opening of the relief-valve, the pressure on the main valve is relieved, 85 and the main valve is then raised from its seat either by the engagement with the valve of the lugs 39, or by the upward pressure of the spring 41 against the main valve. When the piston has risen high enough to 90 uncover the opening 42 and comes to rest the spring 41 continues the upward movement of the main valve until the relief-opening is closed by engagement of the seat 38 with the relief-valve. If, then, the controlling-valve 21 be closed, and the water begins to escape from the cylinder 19, thus permitting the piston 20 to fall, the leakage from the inlet-chamber into the balance-chamber 40 causes pressure to accumulate upon the 95 upper surface of the main valve-member 12, and this pressure, in conjunction with the forced gravity, forces the valve-member downwardly against the opposing spring 41, thus tending to push the piston 20 downwardly and to close the main valve. As soon, however, as this pressure has accumulated to such an extent as to equal and slightly overcome the force of the spring, 100 the main valve is moved downwardly out 100 of engagement with the relief-valve, so that water is permitted to escape, through the open relief-valve, from the balance-chamber to the outlet-chamber. This escape results in reducing the pressure within the balance-chamber. It will be apparent that, as a result of the action just described, the downward pressure of the water in the balance-chamber is automatically regulated so that the sum of this pressure and the force of 110 gravity is approximately equal to the force of the spring 41, and the main valve is thus moved downwardly toward closed position 115 under a uniform water-pressure, of which the amount may be determined by a suitable 120 selection of the spring 41.

125 By the conjoint regulation of the force tending to close the main valve, and the resistance to such closing movement afforded by the adjustable dashpot, the time of opera- 130

tion of the main valve may be exactly determined without regard to the pressure of the water in the inlet-chamber 6 or to any variations in this pressure which may occur.

5 The invention is not limited to the embodiment thereof hereinbefore described and illustrated in the accompanying drawings, but it may be embodied in various other forms within the scope of the invention as 10 it is defined in the following claims.

The invention claimed is:—

1. A flushing-valve having, in combination, a main valve-member; a dashpot, connected with said valve-member, for causing 15 its opening movement and retarding its closing movement, the dashpot having an opening for the inflow and escape of water; a passage connected with said opening and also provided with a restricted escape-opening; manually operable means for admitting water into the passage at a rate faster than it can escape through said escape-opening, whereby the water is caused to fill the dashpot and open the main valve-member; 20 and a check-valve controlling the opening in the dashpot and movable, by the inflow of water, to a comparatively open position, and, by the outflow of water, to a more nearly, but not entirely, closed position.

30 2. A flushing-valve having, in combination, a body provided with a valve-seat and with inlet and outlet passages; a main valve coöperating with said seat and arranged to open against the direction of flow; a hydraulic device connected with the main valve and adapted to act as a motor, to move the valve from its seat, and as a dash-pot, to retard the return of the valve to its seat; and manually-controlled means for admitting water to the hydraulic device, from the inlet, to cause it to act as a motor; the cylinder of the hydraulic device being provided with an escape-opening located in position to be uncovered by the piston near 45 the completion of its operative stroke as a motor, said opening communicating with the outlet-passage.

3. In a flushing-valve, a hydraulic motor and dashpot, for controlling the valve proper, provided with a tapering inlet-and-outlet passage; a combined check-valve and regulating-valve in the form of a ball movable in said passage; a support, for the ball, extending into engagement therewith when 55 the ball is in position to check the outflow

through the opening; and manually-operable means for moving the support to adjust the position in which the ball is arrested.

4. A flushing-valve having, in combination, a single-seated balanced main valve; a relief-valve seated in the main valve; a hydraulic motor and dashpot connected with the relief-valve and the main valve to open them in sequence; and a spring tending to 60 move the relief-valve to closed position with respect to the main valve and in opposition to the action of the motor.

5. A flushing-valve having, in combination, a main valve; a dashpot for producing 70 resistance to the closing movement of the main valve; and means for subjecting the main valve to a closing pressure regulated automatically to a predetermined amount regardless of variations in the pressure in 75 the water-supply.

6. A flushing-valve having, in combination, a single-seated balanced main valve; a dashpot for producing resistance to the closing movement of the main valve; and a 80 spring-controlled relief-valve constructed and arranged to relieve automatically any valve-closing pressure upon the main valve in excess of a predetermined amount.

7. A flushing-valve having, in combination, a main valve; a casing provided with an inlet-passage and an outlet-passage; a guide, for the main valve, adapted to confine water in valve-closing engagement with the main valve and having restricted communication with the inlet-passage; and means including a spring-controlled relief-valve, adjusted to discharge water automatically from the valve-guide into the outlet-passage whenever the pressure in the 90 valve-guide exceeds a predetermined amount during the closing movement of the main valve.

8. A flushing-valve having, in combination, a main valve; means for confining 100 water in valve-closing pressure against the main valve; a dashpot for producing resistance to the closing movement of the valve; and means, actuated by the force of said resistance, for relieving said valve-closing pressure whenever, but not until it rises, 105 during the closing movement of the valve, above a predetermined amount.

CHARLES H. PHILLIPS.
